CLAIM

The ornamental design for a travel mug, as shown and described.

DESCRIPTION

FIG. 1 is a top, front and right perspective view of a travel mug showing my new design.

FIG. 2 is a front elevational view thereof.

FIG. 3 is a right side elevational view thereof, the left side being a mirror image thereof;

FIG. 4 is a rear elevational view thereof;

FIG. 5 is a top plan view of the thereof; and,

FIG. 6 is a bottom plan view thereof.

The portions of the travel mug shown in broken line form no part of the claimed design.

1 Claim, 6 Drawing Sheets(56)
